UNITED STATES PATENT OFFICE.

BERNICE SQUIER AND BLANCHE SQUIER, OF BATTLE CREEK, MICHIGAN.

DESIGN FOR A DOLL.

55,962.

Specification for Design.

Patented Aug. 3, 1920.

Application filed January 8, 1920. Serial No. 350,227. Term of patent 3½ years.

To all whom it may concern:

Be it known that we, BERNICE SQUIER and BLANCHE SQUIER, citizens of the United States, and residents of the city of Battle Creek, county of Calhoun, State of Michigan, (whose post-office address is 149 Fremont street, Battle Creek, Michigan,) have invented a new, original, and ornamental Design for Dolls, of which the following is a specification, reference being had to the accompanying drawing, forming a part thereof.

The figure is a front view of a doll, showing our new design.

We claim:

The ornamental design for a doll as shown.

BERNICE SQUIER.
BLANCHE SQUIER.
